(57) **CLAIM**

The ornamental design for a cheese board, as shown and described.

DESCRIPTION

FIG. 1 is a front, right, top perspective view of a cheese board, showing my new design;

FIG. 2 is a rear, left, bottom perspective view thereof;

FIG. 3 is a front elevational view thereof;

FIG. 4 is a rear elevational view thereof;

FIG. 5 is an enlarged left side elevation view thereof;

FIG. 6 is an enlarged right side elevation view thereof;

FIG. 7 is a top plan view thereof;

FIG. 8 is a bottom plan view thereof;

FIG. 9 is a first partially enlarged view thereof, taken from FIG. 1;

FIG. 10 is a second partially enlarged view thereof, taken from FIG. 1;

FIG. 11 is a third partially enlarged view thereof, taken from FIG. 1;

FIG. 12 is a fourth partially enlarged view thereof, taken from FIG. 2;

FIG. 13 is a fifth partially enlarged view thereof, taken from FIG. 3;

FIG. 14 is a sixth partially enlarged view thereof, taken from FIG. 7;

FIG. 15 is a seventh partially enlarged view thereof, taken from FIG. 8; and,

FIG. 16 is an eighth partially enlarged view thereof, taken from FIG. 8.

The broken lines shown in the drawings for illustrating portions of a cheese board and form no part of the claimed design. The dot-dash broken lines of FIGS. 1, 2, 3, 7 and FIGS. 8–16 are included to show the partially enlarged views only and form no part of the claimed design.

1 Claim, 16 Drawing Sheets
